(57) **CLAIM**

We claim the ornamental design for a hand-held electronic device, as shown and described.

DESCRIPTION

FIG. 1 is a front elevational view of a hand-held electronic device;

FIG. 2 is a rear elevational view thereof;

FIG. 3 is a left elevational view thereof;

FIG. 4 is a right elevational view thereof;

FIG. 5 is a top plan view thereof; and,

FIG. 6 is a bottom plan view thereof.

The broken lines are directed to environment and are for illustrative purposes only; the broken lines and any boundary created thereby form no part of the claimed design.
